UNITED STATES PATENT OFFICE.

D. B. ABBEY, OF HORSE HEADS, NEW YORK.

IMPROVEMENT IN CORN-PLANTERS.

Specification forming part of Letters Patent No. 33,688, dated November 12, 1861.

To all whom it may concern:

Be it known that I, D. B. ABBEY, of Horse Heads, in the county of Chemung and State of New York, have invented a new and Improved Corn-Planter; and I do hereby declare that the following is a full, clear, and exact description of the same, reference being had to the annexed drawings, making a part of this specification, in which—

Figure 1 is a side sectional view of my invention, taken in the line $x x$, Fig. 2; Fig. 2, a plan or top view of the same; Fig. 3, a detached plan or top view of a portion of the mechanism which drives the seed-slide; Fig. 4, a side view of the furrow-share, seed-tube, and covering-share arrangement; Fig. 5, a detached inverted plan of the same.

Similar letters of reference indicate corresponding parts in the several figures.

To enable those skilled in the art to fully understand and construct my invention, I will proceed to describe it.

A represents a rectangular frame, which is mounted on two wheels, B B, and has a driver's seat, C, at its back part.

D is the draft-pole.

The wheels B B are placed on separate or independent axles $a a'$, the axle a' of the wheel B' being longer than the axle a of wheel B. The wheel B' is the driver, as the seed-distributing device is operated from it by the following means: The axle a' has a small wheel, E, upon it, which wheel is provided with a ratchet-face. The wheel E is fitted loosely on axle a' , but by means of a feather is made to turn with the axle.

On the axle a' there is also fitted a cam, F, which is formed of a small drum or wheel having a zigzag or serpentine thread, b, on its periphery, which thread works between two pins, c, at the under side of a lever, G, the back end of which is pivoted to the back part of the frame A, and the front end connected to a seed-slide, H, on the front part of frame A. The cam F has two pins, d d, passing through it, and these pins, when the machine is in use, are kept in contact with the wheel E by means of a bent lever, I, the lever end of which is forked and is behind the wheel E, and the upper end directly over a foot-lever, J, which has a spring, e, bearing against its

under surface, said spring causing the lever J to press upward against the under side of the top of lever I, the lower end of said lever pressing the wheel E against the pins d d of the cam. A small spiral spring, a^x , on the axle a' has a tendency to force the wheel E from the pins d d.

The seed-slide H works beneath two seed-boxes, K K, and to the under side of frame A there are secured, by hinges or joints f, two seed-tubes, L L, one underneath each seed-box K. The seed-tubes L L are connected by a cross-bar, M, which has a hand-lever, N, connected to it, said hand-lever passing up through frame A within reach of the driver. On each seed-tube L there is fitted loosely a collar, g, and to these collars furrow-shares O are attached, one to each collar. The collars g are each connected to the under side of frame A by rods h h, which are allowed to swing underneath the frame. To the lower ends of the seed-tubes L L the stocks or bars P of the covering-shares Q are attached, and the back end of each stock or bar P is connected to the collar g above it by a rod, i.

From this description it will be seen that by actuating the lever N the seed-tubes L may swing forward and the shares O Q elevated above the surface of the ground; and it will also be seen that the driver at any time, by pressing down the lever J with his foot, so that the spiral spring a^x may disengage the wheel E from the pins d d of the cam F, may render the machine operative and inoperative, and the corn therefore may be dropped in check-rows, and no attendant required.

Having thus described my invention, what I claim as new, and desire to secure by Letters Patent, is—

The swinging seed-tubes L, with the collars g fitted on them and provided with the furrow-shares O, in connection with stocks or bars P, attached to the lower ends of the tubes L, and provided with the covering-shares Q, all being arranged to operate as and for the purpose specified.

D. B. ABBEY.
